UNITED STATES PATENT OFFICE.

JOHN F. CONRAD, OF NANTY GLO, PENNSYLVANIA.

ELECTRIC CUT-OUT.

1,176,034.

Specification of Letters Patent. Patented Mar. 21, 1916.

Application filed December 13, 1913. Serial No. 806,543.

To all whom it may concern:

Be it known that I, JOHN F. CONRAD, a citizen of the United States, residing at Nanty Glo, in the county of Cambria and State of Pennsylvania, have invented a new and useful Electric Cut-Out, of which the following is a specification.

The present invention relates to improvements in an electric cut out, one object of the invention being the provision of a manually operated cut out especially adapted for use in connection with trolley lines, and more particularly to lines used in mines, where it is desired to isolate one section of the trolley from the other, and where it is desirable to produce a cut out that does not produce a gap or space at the adjacent ends of the trolley, such ends in this instance being secured together by a sectional clamp, the sections of which are insulated from each other.

A further object of the present invention is the provision of an electrical cut out adapted to be connected to and supported from a sectional trolley clamp, whereby when necessary the switch member may be operated to isolate one trolley section from the other, there being provided a peculiar lapping arrangement between the sections to reduce the arcing to a minimum as the trolley wheel passes such point, the switch itself being provided with a resiliently hung member which when the same is operated to open position will have a tendency to lag and drag from its contact to be finally snapped open to thus reduce the arc at such point when the switch is being opened.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a side elevation of the complete cut out. Fig. 2 is a top plan view thereof. Fig. 3 is a similar view to Fig. 1 taken from the opposite side. Fig. 4 is a section taken on line 4-4 of Fig. 1. Fig. 5 is a section taken on line 5-5 of Fig. 2. Fig. 6 is a side elevation of the block of insulation *per se*. Fig. 7 is a similar view looking from the opposite direc-

tion. Fig. 8 is a lower end view of the block of insulation.

Referring to the drawings, the numeral 1 designates a block of insulation, which has placed above the upper edge thereof, two metal reinforcing plates 2 for the reception of the bolts 3 and 4, said bolts 3 and 4 being extended through such insulation and holding the shoe members 5 and 6 relatively thereto so that their reduced inner terminals 7 and 8, as clearly illustrated in Fig. 1 will have an overlapping effect as regards each other, yet be out of contact and insulated from each other.

The block of insulation 1 as clearly illustrated is recessed from opposite ends upon one edge as at 7' and 8' to provide the trolley wheel engaging edge 1' therebetween. Thus, the reduced inner terminals 7 and 8 are adapted to seat within the respective recesses 7' and 8' and form a continuation of the edge 1', so that the wheel passing from one terminal 7 to the other terminal 8 will engage the edge 1', but before emerging from contact with one terminal 7 will engage the other terminal 8, thus preventing arcing at this point.

Formed integral with the shoe 6 and projecting thereabove in parallel with one side of the insulating block 1 is a plate 9, which is connected fixedly thereto by means of screws 10 so as to provide a rigid support for the supporting lug 11. This supporting lug 11, as clearly illustrated in Fig. 4, is slotted as at 11a. The pin or bolt 12 forms a pivot for the bifurcated end 13 of the main switch actuating lever 14 which may be made of a cheap metal, as for instance iron, and having the offset handle 16 so that the present cut out may be properly and easily manipulated without endangering the operator relatively to the current carried in the trolley T. A pin or bolt 17 is fitted through the lug 11 adjacent the slotted portion 11a thereof and carries the spool end 17' for the reception of the coiled spring 18 having the respective terminals 19 and 20 which normally cross each other and assume the position as shown in Fig. 2. A switch blade 21 is pivoted upon the pin 17 within the slot 11a of the lug 11, and has its free end 22 reduced, there being connected to such blade a pin 23, as clearly illustrated in Fig. 5, which is apertured to receive the free end of the terminal 19 of the spring, there being connected to the lever 14 a similar stud or pin

24 for the sliding reception of the free end of the terminal 20. It will thus be seen that when the handle 16 is manipulated to assume the dotted line position, as shown in Fig. 2, that the movement of the terminal 20 of the spring will through the coil 18 gradually pull upon the terminal 10 so as to move the reduced end 22 of the switch blade 21 out of the contact plates 26, such action being gradual and until the same assumes approximately the position as shown in dotted lines, when the tendency of the terminal 19 will be to move toward the terminal 20 it finally assuming the position, as shown in full lines with the blade 21 against the controlling lever 14 but out of contact with the contact plates 26.

The contact plates 26 are disposed in the path to be engaged by the reduced portion 20 22, are formed integral with or in contact with the shoe 5 and are connected to the same face of the block 1 of insulation as is the plate 9. By this means it will be seen that the current flowing from the shoe 6 will be carried through the copper blade 21 to the shoe 5, although the member 14 will also form a path for the current.

When the parts are in the position as shown in Fig. 2, and the handle 16 is manipulated to open the switch member 21, the spring 18 will permit the movement of the member 14 out of contact with the contact plate 27 before there is sufficient tension thrown upon the terminal 19 of the spring 30 to release the blade or switch 21. Even when such tension is thrown thereupon, the blade 21 is slowly withdrawn and finally when the contact thereof with the plates 26 is reduced to the minimum, the terminals of the spring having a tendency to move toward each other will impart a quick snap to the switch 21 and thus free the same from the contact plates 26 with the least possible

arcing effect at such point. During a movement of these parts, the coil 18 of the spring 45 has a tendency to rotate upon the drum or spool member 17 so that such coils have a winding tension placed upon them which imparts force or pressure to the terminal 19 and consequently therethrough to open the switch blade 21. The ribs 27 and 28 are provided to limit the upward movement of the flanges or rims of a trolley wheel, where the groove in the wheel has worn deep, or when the contact lower edges of the shoes 5 and 6 and the block 1 have been worn. It will be noted that the position of the handle 16 and the rounding of the lug 11 permit the passage thereby of a trolley wheel in case of a jumping trolley wheel, without endangering the switch, or operating it.

What is claimed is:

A circuit breaker, comprising a block of insulation, one edge portion of which is recessed from opposite ends so that the ends of the recesses toward the center of the block overlap to produce a trolley wire receiving edge intermediate the recesses, two metal shoes fitting in said recesses, two metal plates resting against the edge of the block 70 opposite the aforesaid edge, bolts piercing the plates and block and locking the respective metal shoes to the block, a portion of each shoe being extended upwardly against the face of the block, said extensions being 75 upon the same face of the block, and a manually controlled switch connected to one extension for contact with the other extension.

In testimony that I claim the foregoing as my own, I have hereto affixed my signature 80 in the presence of two witnesses.

JOHN F. CONRAD.
